UNITED STATES PATENT OFFICE

CARL R. HENNICK, OF CLEVELAND, OHIO, ASSIGNOR TO THE EBERHARD MANUFACTURING COMPANY, OF CLEVELAND, OHIO, A CORPORATION OF OHIO

HOOD FASTENER

Application filed September 10, 1928. Serial No. 305,110.

This invention relates to hood fasteners of the type used on motor vehicles for holding the hood down in its proper position. The present invention constitutes an improvement over the constructions shown in my pending applications, Serial Nos. 119,642 and 119,643.

In the arrangement shown in said applications, the hold-down element is in the form of a lever having one resilient arm and one rigid arm. The rigid arm carries a spring barrel with a hold-down hook at its upper end, while the resilient arm has a portion adapted to bear against the side of the hood 15 to press it in. The lever is pivoted by reason of its passing under a bridge disposed between the two arms.

I have found that an improved bearing for the lever can be obtained by flattening the portion of the lever which passes under the bridge into the form of a spring and making both arms of the lever substantially rigid.

The invention may be readily understood by reference to the accompanying drawing, 25 in which—

Figure 1 is a side elevation, partly in section, of the hold-down device in operative position;

Figure 2 is a similar view of the fastener 30 in its released position;

Figure 3 is a view similar to Figure 1 of a slightly modified construction; and

Figure 4 is a front elevation of the catch plate used in conjunction with the fastener.

In the drawings, A designates the side of the hood to be held down and B designates the flange along the bottom of the vehicle frame against which the side of the hood bears.

Secured to the hood A is a catch plate which is preferably formed of pressed metal and which comprises a body 2 having pads 3 at each side thereof near the top through which rivets are passed for securing the plate in place. Between the pads 3 the body is bent at 4 to form a pocket 5 for cooperation with the hold-down mechanism hereinafter described.

On the lower end of the body 2 is a portion 2^a having a beveled opening therethrough in

which is inserted a button 6 of leather or other material for preventing unsightly wear or chafing by the fastener, as hereinafter described.

Secured to the vehicle body at 7 is a bridge 55 member 8 which may be formed of pressed metal or which may be cast, having upstanding ears 9 between which extends a pin 10.

The hood fastener comprises a lever member 11 having an outer arm 12 and an inner arm 13. Both arms are formed of heavy metal stock. The arm 13 has a flat pad 14 at its upper end adapted to bear against the button face when it is in the position shown in Figure 1.

The arm 12 has a sliding barrel 15 thereon with a handle or eye 16 at the upper end. The eye carries a hook 17 adapted to project into the pocket 5. The barrel 15 is urged down by a compression spring 18 inside the barrel confined between the lower end of the barrel and a washer 19 on the upper end of the lever stem 12. The portion of the lever which connects the arms 12 and 13 is flat in cross-section and is tempered to provide a spring. This flat portion is designated 20. When the fastener is in the position shown in Figure 1, the pad 14 pressing against the button 6 creates a pressure against the spring portion 20, so that the side of the hood A is urged inwardly while the hook 17 holds the hood down.

The ears 9 of the bridge have cut-out portions 9^a for cooperation with the lower end of the barrel 15. The lower end of the barrel 15 is tapered and when the fastener is in released position, as shown in Figure 2, the end of the barrel bears against the tops of the ears 9. This maintains the fastener in the position shown in Figure 2 and prevents it from falling back.

The arrangement shown in Figure 3 is substantially the same as that shown in Figure 1. In this construction the fastener has a lever 21 having two arms 22 and 23. The arm 22 is similar to the arm 13 and has a pad 24 at its upper end. The arm 23 instead of having an outwardly projecting portion for cooperation with the barrel, carries a separate pin 25 on which the barrel 26 with its

hold-down eye 27 is carried. The arms 22 and 23 are connected by a flat spring portion 28.

By providing a flat spring portion between the two arms of the lever, a construction is provided wherein the side of the hood is urged inwardly as it is pulled down, and a flat bearing for the lever under the bridge is obtained. A stiff and powerful spring can be provided in this portion of the fastener.

While I have shown certain preferred embodiments of the invention, it will be understood that the invention is not limited to the particular construction of parts herein specifically illustrated and described.

I claim:

1. In a hood fastener, a bridge, an integral lever passing under the bridge having a pair of arms, one arm having a hood engaging portion thereon, a hold-down barrel slidably carried on the other arm, the portion of the lever between the two arms and passing under the bridge comprising a spring.

2. In a hood fastener, a lever having a pair of upwardly extending arms connected by a flat relatively stiff spring portion said arms being relatively stiffer than the spring portion connecting them, means on one of the arms for engaging the side of a hood, and a hold-down barrel carried by the other arm.

3. In a hood fastener, a lever having a pair of upwardly extending arms connected by a flat relatively stiff spring portion, means on one of the arms for engaging the side of a hood, a hold-down barrel carried by the other arm, said spring portion of the lever being relatively wide and flat, and a bridge having a cross piece under which the spring portion of the lever passes and against which it bears.

40 In testimony whereof I have hereunto set my hand.

CARL R. HENNICKE.
